UNITED STATES PATENT OFFICE

2,078,077

AUTOMATIC FIDELITY CONTROL

Louis C. Hollands, Verona, N. J., assignor to
Radio Corporation of America, a corporation of
Delaware

Application November 28, 1933, Serial No. 700,034

7 Claims. (Cl. 250—20)

My present invention relates to control circuits for radio receivers, and more particularly to a radio receiver including automatic fidelity control.

It is highly desirable to have a radio receiver, particularly one operating in a broadcast range, possess a variable audio response characteristic. For example, the radio receiver should have a broader audio response characteristic when receiving strong local stations than when receiving relatively weaker distant stations. In the case of the reception of relatively weak signals from distant stations, it is of considerable advantage to substantially reduce the receiver response to the higher audio frequencies since the background noises reside in the higher audio frequency portion of the audio range.

Various arrangements have been proposed heretofore for securing automatic fidelity, or selectivity, control in a radio receiver. In many of these arrangements the resonance curve characteristic of a tuned circuit feeding the audio network is varied according to the change in received carrier amplitude. One of the problems encountered in the practical use of such systems is the increase of interference from an adjacent unwanted station frequency.

Accordingly, it may be stated that it is one of the main objects of the present invention to provide in a radio receiver an automatic fidelity control tube which feeds a tuned network coupled to the audio network of the receiver, and wherein a variable audio response having better fidelity on local stations than on distant stations is obtained, while, at the same time, there is not secured an increase in the interference from an adjacent station frequency above a given amount determined by the set designer.

Another important object of the present invention is to provide a radio receiver which not only includes an automatic volume control arrangement for rendering the intensity of the carrier amplitude fed to the detector substantially constant, but also includes an automatic fidelity control arrangement which functions to vary the overall selectivity curve of a receiver, in such a manner that the receiver more faithfully reproduces signals from a strong local station than from a relatively weaker distant station.

Still another object of the invention is to provide in a superheterodyne receiver provided with an intermediate frequency amplifier feeding the receiver detector through a tuned network an improved type of fidelity control tube in the amplifier whose plate impedance is automatically

regulated in accordance with the variations in the received carrier amplitude, so that the control tube has a minimum plate impedance when receiving strong signals and a maximum plate impedance when receiving relatively weaker signals.

Still other objects of the invention are to improve generally the simplicity and efficiency of broadcast radio receivers, and to particularly provide such a receiver with automatic volume control and automatic fidelity control arrangements which are not only reliable in operation, but add no control elements to be operated manually by the broadcast receiver listener.

The novel features which I believe to be characteristic of my invention are set forth in particularity in the appended claims. The invention itself, however, both as to its organization and method of operation, will best be understood by reference to the following description, taken in connection with the drawing, in which I have indicated diagrammatically a circuit organization whereby my invention may be carried into effect.

In the drawing:—

Fig. 1 shows diagrammatically a receiving system embodying the present invention.

Fig. 2a shows the resonance curve characteristic of the first intermediate frequency amplifier, which is predetermined by the set designer.

Fig. 2b graphically shows the resonance characteristics of the second intermediate frequency amplifier, as a result of the automatic control.

Figs. 3 and 4 graphically illustrate the overall selectivity curve of the receiver of Fig. 1 when receiving weak and strong signals respectively.

Referring now to the accompanying drawing, wherein like reference characters in the different figures designate similar elements, there is shown in Fig. 1 a radio receiving arrangement, which arrangement is shown as of the superheterodyne receiver type, for the purpose of illustrating the present invention. The signal collector comprises the usual grounded antenna circuit 1, and this circuit is connected to a tunable radio frequency amplifier, which is conventionally represented. Those skilled in the art are well acquainted with the construction of the radio frequency amplifier, and it is preferred that this construction be similar to present-day construction. The output of the radio frequency amplifier is impressed upon a combined first detector and tunable local oscillator circuit. Of course, the first detector and oscillator network can either employ two separate tubes, one of the tubes func-

tioning as the first detector and the other tube as the local oscillator, or a single tube functioning as a combination detector and oscillator may be utilized. Both of these arrangements are well known to those skilled in the art at the present time, and, therefore, further explanation is not believed necessary. If a combined first detector and local oscillator circuit is employed, there may be used for such a circuit a 2A7 tube (pentagrid converter tube), as disclosed by Haines application Serial No. 663,171, filed March 28, 1933.

The intermediate frequency energy of the first detector is then impressed upon an intermediate frequency amplifier, which is tuned to an intermediate frequency of 175 kilocycles. This first intermediate frequency amplifier is a band pass amplifier, and its resonance curve characteristic is illustrated in Fig. 2a. The design of the 175 k. c. band pass amplifier is such that it passes the maximum band of the receiver (12 k. c.) at 90% of resonance value. At this point it is pointed out that one of the conditions imposed as satisfactory operation is that the overall selectivity of the receiver must vary from 4 kilocycle band width at 90% of resonance value to 12 kilocycle band width, with substantially the same interference ratio at, for example, 20 kilocycles off resonance. Hence, the resonance of curve characteristic in Fig. 2a shows that the first intermediate frequency amplifier is designed so that at 20 kilocycles off resonance it gives the desired interference ratio. The output of the 175 k. c. amplifier is fed into a second detector network. This network, while shown as a combined second detector and local oscillator network, may employ two separate tubes, one of them functioning as the second detector, while the other functions as a local oscillator. In either case, the local oscillator is fixed, and not variable, as in the case of the first detector network. The second detector network changes the frequency of the output from the first intermediate frequency amplifier to a second lower intermediate frequency of a value of, for example, 40 to 50 kilocycles.

This second intermediate frequency is introduced into a second intermediate frequency amplifier through a resonant network 2, which is tuned to the second intermediate frequency of 40 kilocycles. The second intermediate frequency amplifier utilizes a tube 58 of the pentode type. That is to say, the tube 58, besides including the usual signal grid, cathode, positive screen grid and anode, also includes a suppressor grid between the screen grid and anode.

The suppressor grid is denoted by the numeral 3, and this tube 58 functions as the automatic fidelity control tube. A third detector follows the tube 58, and the coupling between the plate of tube 58 and the input electrodes of the third detector includes a transformer 4, which possesses a tuned primary and a tuned secondary both tuned to the second intermediate frequency of 40 kilocycles. The amplifier network including tube 58 is designed to have a selectivity curve similar to curve 1' of Fig. 2b when the plate impedance of tube 58 is a maximum. The latter condition holds true when the voltage of the suppressor grid 3 is at cathode potential. At 90% of resonance the band width is to be 4 kilocycles. Now, with minimum plate impedance the selectivity curve of this amplifier will assume some such shape as shown by curve 2' of Fig. 2b. This latter curve results because the tuned circuits of the transformer 4 are shunted by the low plate impedance 75 of the automatic fidelity control tube 58.

The detector output of the third detector is fed into an audio frequency amplifier, and the audio output of the latter is reproduced in any well known manner, as by a loud speaker. The control voltage for the fidelity control function and the volume control function is derived from a rectifier 5 arranged to have signal energy impressed upon it through a signal path 6 from the input circuit of the third detector. The rectifier may be of the diode or triode type, and in either case the direct current component of the rectified signal voltage is employed for the two control functions. It is not believed necessary to show the detailed circuit connections of the rectifier 5 for the reason that its construction is well known to those skilled in the broadcast receiver art at the present time. Reference is made to application Serial No. 642,544, filed November 14th, 1933 by Chittick, et al. for an illustration of an arrangement which may be employed to secure the control voltages in this case.

The automatic volume control path includes the direct current connection 7 between the rectifier 5 and the grid circuits of the radio frequency amplifier, the first detector and the 175 k. c. intermediate frequency amplifier. Such a volume control path customarily includes the resistor-condenser filter arrangement 8 for suppressing ripples in the volume control voltage. Of course, the functions of the rectifier 5 and the third detector may be combined in a single tube, and such a construction is also very well known to those skilled in the art, the direct current component of the detector plate current being employed in that case for the volume control function. The direct current component of the rectified signal voltage of rectifier 5 is also employed to control the direct current voltage of the suppressor grid 3, and this is accomplished through a lead 9, a radio frequency filter 10 being connected between ground and the lead 9.

The main limitation of the application of an automatic fidelity control tube, such as tube 58, in a radio receiver is that when the tube has minimum plate impedance, the selectivity of the tuned circuit across which it is placed is very materially broadened. This means that the voltage input from the interfering station, to give the same audio output as the wanted station, becomes less. Another way of explaining this phenomenon is that when the fidelity of the receiver becomes good, less signal strength from an interfering station is required to give the same audio output as that from the desired station. It is for this reason that the condition, stated heretofore, was imposed for satisfactory operation; to wit: that the overall selectivity must vary from 4 kilocycle band width at 90% of resonance value to 12 kilocycle band width with substantially the same interference ratio at say 20 kilocycles off resonance. The resulting overall selectivity curve of the receiver is arrived at by combining the two selectivity curves of the second intermediate frequency amplifier with that of the first intermediate frequency amplifier. These results are shown in Figs. 3 and 4.

In Fig. 3 the shaded portion S shows the overall selectivity or response of the receiver at maximum R_p (plate impedance) of the automatic fidelity tube 58. It will be observed that this curve is obtained by combining curve 1' of Fig. 2b with the curve shown in Fig. 2a. In Fig. 4 the shaded portion S' shows the overall selectivity of the receiver at the minimum plate impedance condition of the tube 58. It will be ob-

served that in both cases the interference ratio at 20 kilocycles off resonance is better than the band pass amplifier alone, the latter being shown in Fig. 2a. One of the conditions imposed was 5 that the band pass amplifier be designed so that the interference ratio of it alone was as good as was wanted. It would reach this condition as a limit only if there were no selectivity in the second intermediate amplifier at minimum plate 10 impedance of tube 58.

The operation of the receiving arrangement shown in Fig. 1 is as follows:—The action is such that when the amplitude of the carrier is small, as when receiving a distant station, the negative 15 potential generated by the rectifier 5 is small, and the second intermediate frequency amplifier tube's plate impedance is high and loading on its tuned plate circuit is small. Therefore, its selectivity is good. This results in the non-reproduction of the higher frequency side bands of the 20 received signal. This gives a fidelity characteristic which does not reproduce the higher audio frequencies and attendant extraneous high-frequency noise which would accompany the reception 25 of a weak signal. When a strong local signal is received a high negative potential results at the rectifier 5, due to a large carrier amplitude. This large negative potential on the suppressor grid of the second intermediate frequency amplifier 30 tube will cause the tube plate impedance to be reduced to a low value.

This low impedance causes the associated tuned circuit in the plate circuit of this tube to be severely loaded and results in a poor selectivity 35 curve. As a direct result of this reduced selectivity curve the audio fidelity becomes good; which is to say the high frequencies are produced in the audio output. Since the signal is large and produces a large negative voltage at the 40 rectifier, and this negative voltage is used as an automatic sensitivity control on the rest of the receiver, it follows that the sensitivity is also greatly reduced and the receiver becomes less susceptible to extraneous noises.

45 Since the selectivity of the second intermediate frequency amplifier is broad it follows that its reactivity to adjacent channel interference is also reduced. This feature is undesirable and by use of a first intermediate frequency amplifier, as 50 before mentioned, whose selectivity characteristic is controlled by design to give the desired rejection ratio this undesirable feature is eliminated. This is illustrated by combining the selectivity curves of the two intermediate frequency 55 amplifiers which give as a result the overall selectivity characteristic which the third, or audio, detector operates on. This is illustrated by the shaded portions of Figs. 3 and 4 which show the reception of a weak or distant station, and also a 60 strong or local station.

While I have indicated and described a system for carrying my invention into effect, it will be apparent to one skilled in the art that my invention is by no means limited to the particular 65 organization shown and described, but that many modifications may be made without departing from the scope of my invention, as set forth in the appended claims.

What I claim is:—

70 1. In a superheterodyne receiver, an intermediate frequency amplifier, a detector, a resonant network coupling said amplifier and said detector, said network being tuned to the operating intermediate frequency, means for automatically 75 controlling the direct current potential of an

electrode of said amplifier to vary the plate impedance thereof sufficiently to regulate the selectivity of said network, said amplifier comprising a pentode tube provided with a suppressor grid between its screen grid and anode, and said potential varying means including a direct current connection to the suppressor grid. 5

2. In combination, in a superheterodyne receiver, an intermediate frequency amplifier having a band pass characteristic, said amplifier being designed to pass a maximum band of 12 kilocycles at 90% of resonance value, a second detector and a following second intermediate frequency amplifier tuned to a frequency substantially less than the frequency of the first amplifier, said second amplifier means designed to have a band width of 4 kilocycles at 90% of resonance, a rectifier following said second amplifier, and a direct current connection between a cold electrode of said second amplifier and said rectifier 20 for varying the plate impedance of said second amplifier in such a manner that the overall selectivity of the receiver is sharper when receiving weak signals than when receiving strong signals. 25

3. In a superheterodyne receiver including two successive frequency changer circuits for reducing received signals of a frequency from 550 to 1500 kilocycles to a frequency of the order of 40 kilocycles, a detector, an amplifier between the 30 said detector and the preceding frequency changer circuit, said amplifier including a pentode tube provided with a suppressor grid between the screen grid and plate thereof, a rectifier coupled to the plate of the pentode amplifier through a tuned network to receive signal energy therefrom, and a direct current connection from the rectifier to said suppressor grid to vary the amplifier plate impedance and thereby regulate the tuned network selectivity. 40

4. In a radio receiver of the superheterodyne type, at least two successive amplifiers, each amplifier being tuned to an operating carrier frequency, the second amplifier frequency being substantially lower than the first amplifier frequency, a network, tuned to the second amplifier frequency, coupled to the second amplifier, and means, responsive to received carrier amplitude variations, for varying the output impedance of the second amplifier in such a manner that the 50 sharpness of said tuned network is varied in a sense opposite to said amplitude variations. 45

5. In a superheterodyne receiver including two successive frequency changer circuits for reducing received signals of a frequency from 550 to 1500 kilocycles to a frequency of 40 kilocycles, a 55 detector, an amplifier between the third detector and the preceding frequency changer circuit, said amplifier including a pentode tube provided with a suppressor grid between the screen 60 grid and plate thereof, a rectifier coupled to a point in the receiver system to receive signal energy therefrom, a direct current connection from the rectifier to said suppressor grid, and an additional direct current connection between the rectifier and a point in the receiver system preceding 65 said amplifier.

6. In a radio receiver of the superheterodyne type, at least two successive amplifiers, each amplifier being tuned to an operating carrier frequency, the second amplifier frequency being substantially lower than the first amplifier frequency, a network, tuned to the second amplifier frequency, coupled to the second amplifier, and means, responsive to received carrier amplitude 70 75

variations, for varying the output impedance of the second amplifier in such a manner that the sharpness of said tuned network is varied in a sense opposite to said amplitude variations, said 5 last means additionally being constructed and arranged for automatically varying the gain of the first amplifier, in response to received carrier amplitude variations, in a sense inverse to said amplitude variations.

10 7. In a radio receiver, a signal frequency amplifier, a demodulator, a tuned network coupling the amplifier and demodulator, said amplifier including a pentode tube provided with a suppressor

grid between the screen grid and plate thereof, and means, responsive to received signal amplitude changes, connected to the suppressor grid to vary the selectivity of said network in a sense opposite to said amplitude changes, and means, 5 responsive to received signal amplitude variations, for automatically controlling the signal input to said amplifier in such a manner that the signal amplitude at the amplifier input circuit is substantially constant over a relatively wide range 10 of received signal amplitude variation.

LOUIS C. HOLLANDS.
